(57) **CLAIM**

The ornamental design for a fishing lure as shown and described.

DESCRIPTION

FIG. 1 is a perspective view of a fishing lure showing my new design;

FIG. 2 is a front view thereof;

FIG. 3 is a rear view thereof;

FIG. 4 is right side view thereof;

FIG. 5 is a left side view thereof;

FIG. 6 is a top plan view thereof;

FIG. 7 is a bottom plan view thereof;

FIG. 8 is a second perspective view; and,

FIG. 9 is a reference perspective view in a first environment. The broken lines in the drawings are for the purpose of illustrating portions of the fishing lure and form no part of the claimed design.

1 Claim, 7 Drawing Sheets
